WRAPPER SEALING DEVICE

Charles H. Petskeyes, Davenport, Iowa, assignor
to Micro-Westco, Inc., Bettendorf, Iowa, a corporation of Delaware

Application November 22, 1935, Serial No. 51,115

5 Claims. (Cl. 93—2)

This invention relates to heaters for use in connection with the sealing of wrapped articles and more particularly to heaters for sealing bread wrappers.

5 One of the objects of the present invention is to provide sealing plates and the like for wrapped articles with new and simple means for providing a more efficient seal.

Another object is to provide sealing plates for 10 wrapped articles with heated wrapper contacting and sealing elements of new and improved construction which are of such construction that portions of the same will follow the surface of the article wrapper engaged therewith.

15 With the above and other objects in view the present invention consists of certain features of construction and combinations of parts to be hereinafter described with reference to the accompanying drawings and then claimed.

20 In the drawings which illustrate suitable embodiments of the present invention,

Figure 1 is a plan view of the wrapper sealing device of the present invention and so arranged as to be associated with the frame of a wrapping machine.

25 Fig. 2 is a side elevation of the device shown in Fig. 1.

Fig. 3 is a transverse section taken approximately on the line 3—3 of Fig. 1.

30 Fig. 4 is an enlarged section taken approximately on the line 4—4 of Fig. 1.

Fig. 5 is a transverse section taken approximately on the line 5—5 of Fig. 4 showing the manner of mounting the forward wrapper engaging elements.

35 Fig. 6 is a transverse section taken approximately on the line 6—6 of Fig. 4 showing the manner of mounting the rearward wrapper engaging elements.

40 Fig. 7 is a fragmentary plan view of one of the heater side plates and taken as looking in the direction of the arrows 7—7 of Fig. 4, and

45 Fig. 8 is a diagrammatic view showing the passage of wrapped articles such as loaves of bread, over the bottom heater plate.

Referring to the accompanying drawings in which like numerals refer to like parts throughout the several views, the heater device of the present invention includes a bottom support 10 and 50 side rails 11 which may, if desired, form a part of the frame of a wrapping machine. Positioned upon the support 12 is a bottom heater plate 13, the surface of which is formed with a series of inclined portions 14, each of which forms with 55 the next adjacent portion a shoulder 14a.

Extending between the side rails 11 is a rod 15 and a shaft 16 which is parallel thereto. The shaft 16 is journaled in the side rails 11 and is provided with right and left threads 17.

Angle brackets 18 are carried by the rod 15 and shaft 16 and these angle brackets have sliding engagement with the rod 15 and threaded engagement with the shaft 16. The brackets 18 are provided with horizontal portions 19 which are arranged above the plane of the bottom heater plate 13 in slightly spaced relation and the portions 19 support vertically arranged supporting members 20 of channel shaped cross-section. The members 20 face each other as shown in Fig. 3 and are disposed over the bottom heater plate 15 13 in spaced relation.

Side heater plates 21 are removably secured to the supporting members 20, the plates 21 having portions of their surfaces arranged in a manner similar to the surface of the bottom heater plate 20 13.

By rotating the threaded shaft 16 by means of a hand wheel 16a, the members 20 and plates 21 supported thereby, may be moved towards and away from each other to accommodate wrapped articles such as loaves of bread of different lengths.

The present invention resides in the arrangement of the heater elements for the side and bottom plates.

30 Many wrapped articles such as bread having wrappers of waxed paper or cellulose material, in which it is necessary or desirable to seal the wrapper through the application of heat to the overlapping wrapper portions and many articles 35 which are to be wrapped, have irregular contours. For example, the ends of loaves of bread are slightly rounded and frequently the bottom of the loaf is dished inwardly. In heaters used heretofore, no provision has been made for compensating for the irregular contour of the wrapped articles, and, as a result imperfect seals are obtained because due to these irregularities, it is impossible for the overlapping portions of the wrapper which extend over the irregularities, to 45 be firmly pressed together and against the surface of the article.

The bottom heater plate 13 is provided with a series of forward aligned transversely extending slots 22 and a series of aligned rearward transversely extending slots 23 preferably of greater width than the slots 22, the slots 23 being disposed between the slots 22 and the out-feed end of the bottom plate 13 as shown in Fig. 1.

Positioned within each of the forward slots 22 55

is a tubular metal member 25 which is capable of efficiently transmitting heat, and positioned in each of the rearward slots 23 is a rectangular member 25a which is also of a metal capable of efficiently transmitting heat. The tubular members 25 are freely movable in the slots 22 but are held against inadvertent displacement by means of a rod 26 which extends therethrough as shown in Figs. 4 and 5 and which is secured to the heater plate 13 by means of suitable clamps 27. The rectangular members 25a are connected together by suitable rods 28 and the end-most members 25a are provided with outwardly extending rod-like portions 29 which are secured to the heater plate 13 by means of clamps 30 as shown in Figs. 4 and 6. The forward edge of each of the rectangular members is beveled at 25b as shown in Figs. 4 and 8.

Suitable electric heating elements 31 are resiliently held in contact with the tubular members 25 and the rectangular members 25a for heating these members, the upper surfaces of the members 25 and 25a, being arranged above the plane of the bottom heater plate 13 as shown in Fig. 8. An additional electric heating element 32 may be arranged, if desired, to contact with the side of the heater plate 13 in advance of the tubular members 25 as shown in Fig. 4.

If desired, suitable inclined plates 33 may be secured to the plate 13 slightly in advance of the members 25 to assist in the movement of the forward end of the wrapped article over these members.

Assuming, for example, that the wrapped article is a loaf of bread and that the bottom is slightly dished as shown, in Fig. 8, movement of the loaf along the plate 13 causes the leading end of the loaf to ride up and over the tubular members 25. During continued movement of the loaf along the plate 13, the overlapping portions of the wrapper at the bottom of the loaf are caused to engage the bottom of the loaf by reason of the tubular members 25, thus insuring a firm contact of these overlapping wrapper portions with the members 25 and the bottom of the loaf, whereby the same are heated to melt the wax in the case the wrapper is waxed paper, or to fuse these overlapping portions together in the case where the wrapper is of cellulose material. The tubular members 25 provide for a line contact between the overlapping wrapper portions which insures a perfect seal. The rectangular portions 25a function in a manner similar to the portions 25 and insure a firm contact between the overlapping wrapper portions but over a substantial area so that these wrapper portions are in complete contact, whereby to provide for an efficient heating and sealing of these portions.

If desired, depending upon the character of the wrapped articles, the vertical side plates 21 may also be provided with a similar arrangement of heating elements such as shown in Figs. 4 and 7. As shown in these views, the side plate 21 is provided with slots 34 and 35, a vertical tubular wrapper contacting element 36 being mounted in the slot 34 and a rectangular wrapper contacting element 37 being mounted in the slot 35. Electric heating elements 38 are arranged between the elements 36 and 37 and the supporting member 20 as shown in Fig. 3, which elements heat the members 36 and 37 so that these members will contact with the overlapping end portions of the wrapper and provide for an efficient seal in a manner similar to the members 25 and 25a, previously described.

The sealing devices of the present application are an improvement upon the sealing devices disclosed and claimed in my copending application, Serial No. 726,346, filed May 18, 1934, for Wrapping machine.

Furthermore, it is to be understood that the particular form of apparatus shown and described and the particular procedure set forth are presented for purposes of explanation and illustration and that various modifications of said apparatus and procedure can be made without departing from my invention as defined in the appended claims.

What I claim is:

1. In a device for heating the overlapping portions of the wrapper of a wrapped article, an article guiding member having a series of fixed, unyielding wrapper smoothing ridges extending across the article contacting face of the member transversely of the direction of movement of the wrapped article, a slot in the face of the member, a wrapper engaging element arranged to be loosely carried in the slot and extending beyond the ridges, said element resiliently supported to follow the contour of a wrapped article passing across the slot and arranged to be maintained in contact with an electrical heating element, whereby a wrapped article may have its wrapper smoothed by the ridges and overlapped portions of the wrapper pressed together by a heated element.

2. In a device for heating the overlapping portions of the wrapper of a wrapped article, an article guiding member having a series of fixed, unyielding wrapper smoothing ridges extending across the article contacting face of the member transversely of the direction of movement of the wrapped article, a slot in the face of the member, a wrapper engaging element arranged to be loosely carried in the slot and extending beyond the ridges, said element having a curved article contacting surface for engaging depressed portions of the wrapped article and resiliently supported to follow the contour of a wrapped article passing across the slot, and arranged to be maintained in contact with an electrical heating element, whereby a wrapped article may have its wrapper smoothed by the ridges and overlapped portions of the wrapper pressed together by a heated element.

3. In a device for heating the overlapping portions of the wrapper of a wrapped article, an article guiding member having a series of fixed, unyielding wrapper smoothing ridges extending across the article contacting face of the member transversely of the direction of movement of the wrapped article, a slot in the face of the member, a wrapper engaging element arranged to be loosely carried in the slot and extending beyond the ridges, said element having a flat faced article contacting surface for engaging level portions of the wrapped article and resiliently supported to follow the contour of a wrapped article passing across the slot and arranged to be maintained in contact with an electrical heating element, whereby a wrapped article may have its wrapper smoothed by the ridges and overlapped portions of the wrapper pressed together by a heated element.

4. In a device for heating the overlapping portions of the wrapper of a wrapped article, an article guiding member having a series of fixed, unyielding wrapper smoothing ridges extending across the article contacting face of the member transversely of the direction of movement of

- the wrapped article, two or more slots in the face of the member, wrapper engaging elements arranged to be loosely carried in the slots and extending beyond the ridges, said elements resiliently supported to follow the contour of a wrapped article passing across the slots and arranged to be maintained in contact with an electrical heating element, at least one of said elements having a curved article contacting surface
- 5 for engaging depressed portions of the wrapped article, and at least one of said elements having a flat faced article contacting surface for engaging level portions of the wrapped article, said elements being spaced from one another in the direction of movement of the wrapped article and the intervening space having a portion of the ridged article guiding member positioned therein, whereby a wrapped article may have its wrapper alternately smoothed by the ridges and
- 10 overlapped portions pressed together by heated elements.
- 15 5. In a device for heating the overlapping portions of the wrapper of a wrapped article, an article guiding member having a series of fixed, unyielding wrapper smoothing ridges extending across the article contacting face of the member transversely of the direction of movement of the wrapped article, a slot in the face of the member, a wrapper engaging element arranged to be loosely carried in the slot and extending beyond the ridges, an electrical heating element in contact with said element, said heating element resiliently supported and arranged to urge the wrapper engaging element against the wrapped article to follow the contour of the article and press overlapped portions of the wrapper together while heating them.

CHARLES H. PETSKEYES.
